7 Claims. (Cl. 272—32)

This invention relates to amusement apparatus and more particularly to apparatus which can be propelled by swimmers or bathers which offers a high degree of spinning and tilting characteristics.

It has been conventional practice in the amusement field to employ a tiltable and rotatable float which supports swimmers or bathers and which is anchored at the bottom of the water in which it is to be used, such as the bottom of a swimming pool, for example. Such an apparatus is described in U.S. Patent No. 1,722,523, which provides a whirtable anchored float capable of supporting heavy loads and which is especially adapted for use on beaches and in pools to afford amusement for bathers who climb onto the float and during the whirling thereof endeavor to retain their position on the float and avoid being thrown therefrom into the water. This apparatus operates similar to the rotating platforms used on land.

Difficulties have been encountered when using such a float or platform which stem largely from the fact that the tilting action of the apparatus causes a substantial displacement of water and thereby greatly reduces the effectiveness of the apparatus as an amusement device. For example, because of the displacement of water, the speed at which the apparatus may be rotated while tilting is greatly reduced and the rapidity with which the apparatus may be tilted from one position to another, such as encountered when the user shifts his weight, is greatly limited. Furthermore, inasmuch as the apparatus is extremely buoyant, apparatus of conventional design is subject to excessive and rapid movement or displacement in its tilting action so as to unbalance the user and cause him to lose control. Such sensitivity in an apparatus of this type is highly undesirable.

These difficulties are obviated in accordance with the present invention wherein a float having improved roll characteristics is employed which is anchored to the bottom of the water by means of an expandable linkage having at least two universal joints for providing freedom of tilting action. Furthermore, the linkage is provided with a damping means for limiting the sensitivity of the tilting action to a desired limit so that the user has a high degree of control over the tilting at all times regardless of weight or loads placed on the float.

Therefore, it is a primary object of the present invention to provide a water saucer having improved roll characteristics and greater freedom of action than provided in conventional apparatus.

It is another object of the present invention to provide a tiltable water saucer for the amusement of swimmers or bathers which does not displace water while in action so that the saucer's ability to rotate or spin is effectively unretarded.

Still a further object of the present invention is to provide a water saucer having a configuration which allows for maximum buoyancy and which allows the saucer to rest higher in the water than is possible with conventional apparatus.

Still another object of the present invention is to

2

provide a means for controlling the tilting action of the water saucer from one position to another so that the tilting action is under the control of the user at all times.

Another object of the present invention is to provide 5 a water saucer having means for forcibly urging the saucer to an upright position whereby said force is a function of the tilting angle of the saucer from the vertical plane or upright position.

A further object of the present invention is to provide 10 a water saucer which may move in a vertical plane while the saucer is spinning or at rest, the extent of movement being predetermined and adjustable.

These and other objects will be more apparent from 15 a reading of the following description when taken with reference to the accompanying drawings, in which:

Figure 1 is a perspective view of a water saucer incorporating the present invention shown floating in a body of water;

Figure 2 is an elevational view of the water saucer 20 shown in Figure 1 including the extendable linkage connecting the water saucer to a suitable anchor; and

Figure 3 is an enlarged sectional view of the linkage connecting the water saucer to the anchor including means for controlling the rate of tilting action or motion.

25 The apparatus of the present invention may be constructed in many different forms but in the present instance is shown in the form of a float 10 of a spherical or rounded bowl configuration having a platform 11 suitably secured thereto. Platform 11 is provided with 30 several annular beads 12 which are integrally formed in the platform and serve as reinforcing members or stiffeners so that the platform can assume the weight of several persons and provide these persons with some form of a gripping surface. Between the platform and 35 the float, there is provided an air chamber 13 which adds to the buoyancy of the float. Although the float may be constructed of many materials, it is preferred to employ a laminated fiber-glass construction because of its light weight and high strength characteristics.

40 Extending through the center of the platform and the apex of the bowl and made integral therewith or permanently affixed thereto in any suitable manner, is a fiberglass sleeve 14 which extends above the platform and below the bowl. Sleeve 14 operates as a hub for the float 10 and is connected to a steel tube 15 which rotates with sleeve 14. A shaft 16 extends loosely through the tube 15 and has a hand wheel 17 fixed to the upper end thereof so that the float 10 and sleeves 14 and 15 can revolve relative to shaft 16 and hand wheel 17. The float 10 may rotate about shaft 16 and, as will be later described, the hand wheel will be biased downwardly against the upper end of tube 15. The lower end of shaft 16 has a stop 16' which supports the staple 18 and this stop serves to limit the downward movement of 45 the float 10 and tube 15 relative to shaft 16. The sleeve 15 is formed of upper and lower sections secured together by collar 28 and a collar 30 is secured to the lower end of tube 15 to serve as a stop for engaging stop 16'.

50 The lower end of shaft 16 is connected by a first universal joint comprising a pair of cooperating staples 18 and 19 to the upper end of an extendable linkage represented by numeral 20 while the lower end of the linkage is connected to an anchor 21 by a second universal joint comprising a staple 22 and a part of the anchor 21. The anchor may be of any suitable or desired construction and is shown here in the form of a reinforcing rod 23 bent with the ends thereof extended in opposite directions to form a secure connection with the anchor 21. The anchor is preferably constructed of concrete and 55 may be of any desirable shape and suitable size to insure the anchoring of the float at the bottom of the water in which it is to be used. The anchor is provided with an 60 65 70

open cavity 24 into which a portion of rod 23 projects in order to form a part of the second universal joint in cooperation with staple 22.

Hand wheel 17 is secured to the upper end of shaft 16 by any suitable means such as by a set screw arrangement for example. The handwheel may be either in the form of a disc or may be provided with a plurality of spokes 25 which radiate from a collar 26 carried on the upper end of tube 15 outwardly into attachment with a common ring 17.

Linkage 20 may be said to comprise an elongated cylinder 31 having a cap 32 secured to its upper end and fastened to the first universal joint via staple 19 and an inner collar 33 secured to the inside diameter of the cylinder through which a hollow piston 34 passes as shown more clearly in Figure 3. Collar 33 in cooperation with a collar 35 carried on the upper end of piston 34 maintains piston 34 in a substantial coaxial relationship with cylinder 31 as the linkage is extended and retracted. The lower end of piston 34 is provided with a cap 37 in threaded engagement with the piston which carries the U shaped member or staple 22 forming a part of second universal joint which is engageable with the exposed portion of rod 23. To prevent a forceful engagement of collars 33 and 35, a shock absorbing spring 40 is disposed about piston 34 between the two collars which prevents abrupt contact therebetween.

It has been found desirable to provide a means for maintaining the float in a substantial vertical plane and which will return the float to a substantially vertical plane from a tilted position. This means comprises, a pin 41 which passes through the top of cylinder 31 and which is secured thereto by upsetting the end thereof so that the rod cannot be disengaged from the cylinder, and a similar pin 42 secured in a similar fashion to the lower end of piston 34 at right angle to the pin 41. A pre-loaded spring 43 is connected between pins 41 and 42, respectively, which continually exerts a force on the cylinder to draw the cylinder over the piston in the direction of anchor 21. This action in turn pulls the shaft 16 into an upright position via the first universal joint. Also, the preload of spring 43 causes hand wheel 17 to be forced against the upper end of tube 15 so that the float 10 is preloaded. Therefore, a vertical weight equal to the preload weight can be applied to platform of the float before any downward movement of the float will result. Any such downward movement would cause cylinder 31 to move downward under the force of spring 43 until the lower end of the cylinder engages cap 37. The preload on spring 43 is normally sufficient that engagement would not result. Also, spring 43 absorbs the torque load between the wheel and the anchor to prevent the hand wheel from rotating. Overlapping guides could be added, in slide arrangement, between and on piston 34 and cylinder 31 to absorb the torque load which would be otherwise imparted to spring 43.

In order to prevent the piston and cylinder arrangement from extending or retracting at a rate which might be considered excessive for controlling the tilting action of the float, a dash pot arrangement 44 is provided which is suitably clamped to the cap 32 carried on the upper end of cylinder 31 by means of a conventional strap clamp means 45 and a second strap clamp means 46.

Dash pot 44 comprises, in general, a hollow body 47 having an upper and lower cap 48 and 50 which closes the interior of the body and a moving calithaform piston 51 which is carried in a cavity 52 of the body. The piston is arranged to travel within the cavity about a threaded shaft 53 projecting through the lower cap 50. Shaft 53 passes through a threaded internal bore of a sleeve 54 which is provided with external threads for engagement with mating threads of a bore 55 provided in the lower cap 50. Several wing nuts 56 are carried of the sleeve and shaft exteriorly of the body for the purpose of adjustment of the sleeve and shaft and to secure the adjusted

position of the sleeve or shaft relative to each other and/or to the body.

On the end of shaft 53 projecting into cavity 52, there is secured a retaining nut 57 which retains a washer 58 on the shaft. Washer 58 is urged against the retaining nut by the force of a helical spring 60 disposed about the shaft and having its opposite ends expended against the washer and the bottom of the cavity. Acting against the force of spring 60 is another helical spring 61 which is disposed about the bottom of the piston and a washer 62 abutting against the top of sleeve 54.

A pin and slot arrangement 63 is employed to prevent the piston from rotating within the body and yet to permit vertical displacement of the piston. Body 47 and piston 51 are provided with apertures 64 and 65, respectively, which communicate the cavity exteriorly of the body. The degree of communication is dependent upon the relative position of the apertures so that the flow of water through the apertures is regulated between a condition of small water flow and a condition of maximum flow.

The interior of body 47, including cavity 52, is in communication with the interior of cylinder 31 and piston 34 via a piping arrangement 66 which is connected between a port 67 in cap 48 and a port 70 in cap 32. Thereby, water surrounding the dash pot may be drawn into the dash pot and into the cylinder 31 via piping 66 in response to a withdrawal of the cylinder from about piston 34. The water pressure on the lower side of piston 51 which will act against the pressure on the upper side of the piston is predetermined by adjusting the size of opening 71, which communicates with the interior of the body. The size of the opening is adjustable by selecting the position of lock nut 72 on the shaft 73 containing the opening 71. The strength of springs 60 and 61 determines how far the piston 51 will move to close orifice 64 in relation to the water pressure developed in cylinder 31 caused by movement of the float and the size of opening 71 determines the rate of movement of the piston 51.

When the apparatus of the present invention is properly installed in a body of water, bowl 10 will float in the water and will be held substantially upright from its anchor 21 by means of the spring 43 which urges cylinder 31 over piston 34 to pull shaft 16 downward. The first and second universal joints serve to prevent the shaft 16 from fully rotating about the anchor although limited rotation is permitted. In use, a swimmer or bather climbs onto platform 12 and grasps hand wheel 17 while implanting his feet firmly on the platform. By grasping the hand wheel in a hand over hand fashion, the float 10 will rotate about tube 15 and shaft 16 affixed thereto. As the user, or users as the case may be, shifts his weight on the platform, float 10 will tilt so that the loaded portion of the float sinks into the water while its unloaded portion rises above the water surface.

Inasmuch as the first universal joint comprising staples 18 and 19 is located in close proximity to the bottom of the float, the lower end of shaft 16 pivots about the universal joint so that substantially no water displacement occurs. During the tilting movement, the float may be rotated on tube 16 between hand wheel and the collar stop 30. As the lower end of tube 15 and shaft 16 are tilted with the float, cylinder 31 is pulled from over piston 34 against the tension of the spring 43. This action causes a vacuum to exist within the cylinder which draws water into the hollow cylinder and piston via the piping 66 and apertures 64 and 65 in the dash pot 44. Conversely, when the float is tilted to another position, the water contained in the cylinder and piston is forced through the piping 66 and out of the dash pot via apertures 64 and 65. Consequently, it can be seen that the position of the piston 51 of the dash pot and thereby the flow of water through the apertures is controlled. The drawing of water through the apertures or forcing water out of the dash pot through the apertures, in turn, controls

the sensitivity of the apparatus to change from one position of tilt to another.

Various modifications are contemplated by those skilled in the art without departing from the spirit and scope of the invention as hereinafter defined by the appended claims.

What is claimed is

1. An amusement apparatus comprising, an anchor, an extendable linkage having one end universally connected with the anchor, an upright shaft having a universal connection with the other end of the extendable linkage, a float mounted to rotate on the shaft, the float including a platform having a spherical shaped air chamber on the bottom thereof through the apex of which and the center of the platform the shaft extends, means carried on the extendable linkage for preventing the rotation of the shaft and a hand grip fixed to the shaft to provide for the rotation of the float by users of the apparatus changing their hand holds on the grip.

2. The invention as defined in claim 1 wherein the extendable linkage includes a preloaded resilient means urging the linkage and the shaft to an upright position respective to the anchor.

3. The invention as defined in claim 1 wherein the float is of a fixed height and including stop means secured to the lower end of the shaft which cooperates with the hand grip so that the float has limited vertical movement between the stop means and the hand grip.

4. An amusement apparatus comprising, a float including a reinforced platform having a spherical shaped air chamber on the bottom thereof, an upright shaft extending through the apex of the air chamber and the center of the platform, a sleeve fixed to the float for rotatably mounting the float on the shaft, an anchor, an extendable linkage having a universal connection with the anchor, another universal connection coupling the shaft to the other end of the extendable linkage, means carried

on the extendable linkage for preventing the rotation of the shaft and a hand grip fixed to the shaft to provide for rotation of the float by users of the apparatus changing their hand holds on the grips.

5. The invention as defined in claim 4 including means carried on the linkage for restricting extension and retraction of the linkage in response to the deviation of the shaft from an upright position by the user shifting his weight.

10 6. An amusement apparatus comprising, a float including a reinforced platform having a spherical shaped air chamber on the bottom thereof, an upright shaft extending through the center of the air chamber and the center of the platform, a sleeve fixed to the float and rotatably mounted on the shaft, an extendable linkage having a cylinder enclosing a piston, a first universal joint coupling the anchor to the piston, a second universal joint coupling the shaft to the cylinder so that the linkage extends responsive to deviation of the shaft from its upright position, damping means carried by the cylinder for restricting the extension and retraction of the piston and cylinder, and a hand grip fixed to the shaft to provide for rotation of the float by users of the apparatus changing their hand holds on the grips.

20 7. The invention as defined in claim 6 including resilient means coupling the piston and cylinder of the extendable linkage urging the linkage and shaft into an upright position respective to the anchor.
